(57) **CLAIM**

I claim the ornamental design of a throwing game board, as shown and described.

DESCRIPTION

FIG. 1 is a perspective view of a throwing game board configured to commence the game.

FIG. 2 is a front elevation view of the throwing game board of FIG. 1.

FIG. 3 is a rear elevation view of the throwing game board of FIG. 1.

FIG. 4 is a rear perspective view of the throwing game board of FIG. 1.

FIG. 5 is a first side elevation view of the throwing game board of FIG. 1; the second side elevation view thereof is a mirror image.

FIG. 6 is a top plan view of the throwing game board of FIG. 1.

FIG. 7 is a bottom plan view of the throwing game board of FIG. 1.

FIG. 8 is a perspective view of a second embodiment of a throwing game board of FIG. 1, shown in an alternate playing configuration.

FIG. 9 is a front elevation view of the throwing game board of FIG. 8.

FIG. 10 is a rear elevation view of the throwing game board of FIG. 8.

FIG. 11 is a rear perspective view of the throwing game board of FIG. 8.

FIG. 12 is a first side elevation view of the throwing game board of FIG. 8.

FIG. 13 is a second side elevation view of the throwing game board of FIG. 8.

FIG. 14 is a top plan view of the throwing game board of FIG. 8.

FIG. 15 is a bottom plan view of the throwing game board of FIG. 8.

FIG. 16 is a perspective view of a third embodiment of a throwing game board of FIG. 1, shown in an alternate playing configuration.

FIG. 17 is a front elevation view of the throwing game board of FIG. 16.

FIG. 18 is a rear elevation view of the throwing game board of FIG. 16.

FIG. 19 is a rear perspective view of the throwing game board of FIG. 16.

FIG. 20 is a first side elevation view of the throwing game board of FIG. 16; the second side elevation view thereof is a mirror image.

FIG. 21 is a top plan view of the throwing game board of FIG. 16.

FIG. 22 is a bottom plan view of the throwing game board of FIG. 16.

(Continued)

FIG. 23 is a perspective view of a fourth embodiment of a throwing game board of FIG. 1, shown in an alternate playing configuration.

FIG. 24 is a front elevation view of the throwing game board of FIG. 23.

FIG. 25 is a rear elevation view of the throwing game board of FIG. 23.

FIG. 26 is a rear perspective view of the throwing game board of FIG. 23.

FIG. 27 is a first side elevation view of the throwing game board of FIG. 23.

FIG. 28 is a second side elevation view of the throwing game board of FIG. 23.

FIG. 29 is a top plan view of the throwing game board of FIG. 23; and,

FIG. 30 is a bottom plan view of the throwing game board of FIG. 23.

The broken lines shown in the drawings are included for the purpose of illustrating portions of the throwing game board that form no part of the claimed design.
